DESIGN FOR A JAR

Harold M. Gehm, Alton, Ill., assignor to Owens-Illinois Glass Company, Toledo, Ohio, a corporation of Ohio

Original No. 126,977, dated May 6, 1941. Serial No. 99,815, March 24, 1941. Application for reissue July 24, 1941, Serial No. 102,456. Term of patent 14 years

To all whom it may concern:

Be it known that I, Harold M. Gehm, a citizen of the United States, residing at Alton, in the county of Madison and State of Illinois, have invented a new, original, and ornamental Design for a Jar, of which the following is a specification, reference being had to the accompanying drawing, forming a part thereof.

In the drawing:

Fig. 1 is a side elevational view of a jar showing my new design.

Fig. 2 is a top plan view illustrating a portion of the shoulder decoration.

The surface decorations illustrated are repeated on the opposite side of the jar.

I claim:

The ornamental design for a jar, substantially as shown and described.

HAROLD M. GEHM.
